UNITED STATES PATENT OFFICE.

SAMUEL M. RICHARDSON, OF WOBURN, MASSACHUSETTS.

BREECH-LOADING ORDNANCE.

SPECIFICATION forming part of Letters Patent No. 233,115, dated October 12, 1880.
Application filed July 19, 1880. (No model.)

To all whom it may concern:

Be it known that I, SAMUEL M. RICHARDSON, of Woburn, county of Middlesex, State of Massachusetts, have invented an Improvement in Ordnance, of which the following description, in connection with the accompanying drawings, is a specification.

This invention relates to ordnance, and has for its object improvements in mechanism for easily and quickly operating the breech-piece, the said mechanism swinging the breech-piece laterally and returning it to its position at the rear of the gun through the agency of eccentrics, as hereinafter described.

I have also applied to the gun an extractor operated by hooks carried by arms supporting the movable breech-piece, as hereinafter described.

Figure 1 is a side elevation of a gun provided with my improvements, the breech being closed; Fig. 2, a top view thereof; Fig. 3, a rear end view, the breech-piece being turned aside; Fig. 4, a partial longitudinal vertical section on the line $x^2 x^2$, Fig. 2; Fig. 5, a detail of the cam for directing the movement of the breech-piece as it is operated by the eccentrics, and Fig. 6 a detail of the devices for operating the extractor.

The body A of the gun, having trunnions a , may be bored or rifled in any usual manner, and be made of any usual material.

The breech-piece C, provided with the usual firing-pin 5, is carried at the ends of arms $e f$, preferably made in one piece with the breech, the ends of the said arms being shaped to fit eccentrics $g h$ mounted on projections or bearings $i j$, the arms and eccentrics being secured against lateral movement one over the other by means of pins or splines in the eccentric straps entering grooves in the peripheries of the eccentrics. (See Fig. 4.) These eccentrics are rotated to move the arms longitudinally, and consequently the breech-piece, back away from the rear end of the gun by means of links $k k'$, Fig. 1, and dotted lines, Fig. 2, connected with the pins k^2 on the said eccentrics, and with arms $k^3 k^4$ of a rock-shaft, l , held in lugs or bearings m , the rock-shaft deriving movement from a link, n , connected with a slide, o , adapted to be moved by a lever, p , having one or

more handles connected at a point between its ends with such slide.

A locking device, r , shown as a screw and moving with the handle p , co-operating with a sector, s , holds the lever in either of its two 55 positions.

The cartridge t , of any usual or proper make or material, has its rim seated in a cartridge-extractor, u , (see Figs. 3 and 4,) connected with arms v held in suitable guideways in the gun, 60 so that such arms and extractor may be moved longitudinally to eject the cartridge-shell. These arms v are provided with pins w , which are engaged by spring-hooks x , connected at y with the arms $e f$, such arms, when moved 65 longitudinally backward to uncover the breech of the gun, drawing the arms v and cartridge-extractor u outward.

Upon each eccentric I have placed a pin or roller-stud, a' , which is extended into a cam-shaped slot, a^2 , in a plate, a^3 . These cam-slots are so shaped, substantially as shown, that as the arms $e f$ and breech-piece are moved outward along the gun by the eccentrics the said studs, acting against the plates a^3 , cause the 70 breech-piece to be moved laterally away from, and so as to completely uncover, the rear of the gun, as in Fig. 3. As the arms $e f$ continue their movement in the direction of the arrow, Fig. 1, the hooks of the spring-hooks x release 75 the pins w , and the cams or ribs d' , fixed on the arms $e f$, meet the pins w at their upper sides and move the arms v in the opposite direction, thus drawing the extractor u back into the breech of the gun to receive and hold the 80 cartridge.

As the handle p is moved from the dotted to the full line position, Fig. 1, to close the breech-piece, the springs x , as the arms move longitudinally toward the nozzle of the gun, 90 are moved laterally by reason of their inclined ends, which strike the pins w , but after passing the said pins the hooks engage with them. The sights will be all as usual.

The dotted lines at the left of Fig. 4 show 95 the extractor moved out, as it will be when the breech-piece is in the position, Fig. 3.

Instead of moving the slide o by means of the lever t , it is obvious that I might provide one edge of the slide with proper teeth to be 100

engaged by a worm or screw, to thus move the said slide by the worm or screw. This would be desirable in connection with very heavy ordnance, wherein considerable power would be required to move the eccentrics and swing a heavy breech-piece.

I claim—

1. The breech-piece and its arms combined with the eccentrics and mechanism to actuate the eccentrics, substantially as described, to move the arms and breech-piece longitudinally with relation to the gun at each operation of the breech-piece, substantially as described.
2. The breech-piece and its arms combined with the eccentrics to move them longitudinally, and with the stud and cam-slotted plate to cause the breech-piece to be swung laterally away from the breech of the gun, substantially as described.

3. The combination, with the arms *e f* and 20 their hooks, of the extractor and its arms *v*, to operate substantially as described.

4. The arms *e f* and their cams or ribs *d'*, combined with the arms of the extractor provided with pins *w*, to operate substantially as 25 described.

5. The lever *p*, slide *o*, link *n*, and rocking shaft, and links *k k'*, combined with such shaft, and the eccentrics to operate them, substantially as described.

In testimony whereof I have signed my name to this specification in the presence of two subscribing witnesses.

SAMUEL M. RICHARDSON.
